UNITED STATES PATENT OFFICE.

FREDERICK MAEULEN, OF RAHWAY, AND GEORGE L. VAN ALLEN, OF NEWARK, NEW JERSEY, ASSIGNORS TO BAKER & COMPANY, INC., A CORPORATION OF NEW JERSEY.

MOUNT FOR ARTIFICIAL TEETH.

Application filed November 30, 1920. Serial No. 427,344.

To all whom it may concern:

Be it known that we, FREDERICK MAEULEN and GEORGE L. VAN ALLEN, citizens of the United States, and residents, respectively, 5 of Rahway, in the county of Union and State of New Jersey, and Newark, in the county of Essex and State of New Jersey, have invented new and useful Improvements in Mounts for Artificial Teeth, of 10 which the following is a specification.

This invention relates to a mount for artificial teeth for supporting and displaying the same for exhibition, sale or other purposes.

15 Heretofore artificial teeth have been mounted on a card or the like formed of wax or other penetrable material, or having a coating of such material thereon, the teeth being pressed into the wax and being 20 held thereby on the card for display. This method of mounting the teeth necessitates the use of a large amount of wax which becomes easily soiled, unduly soft and flexible in warm weather and too hard in cold 25 weather, and furthermore does not provide a secure support for "diatoric" teeth.

The objects of our invention are to provide a mount for artificial teeth which requires a minimum amount of wax or the 30 like; to provide such a mount which is rigid in construction and will not easily bend or break; to provide a construction whereby ample support for the "diatoric" teeth is obtained; to thus form a mount 35 comprising a substantially rigid support or backing having in one surface thereof intermediate its ends a depression to receive wax or the like to support the center artificial teeth of a set, the diatoric or end teeth being mounted upon the backing or support 40 at the ends of the said wax; to provide improved means for mounting the diatoric teeth thus saving a large amount of wax and producing a firm support for the diatorics; and to obtain other results and advantages as may be brought out by the following description.

45 Referring to the accompanying drawings, in which like numerals of reference indicate the same parts throughout the several views,

50 Figure 1 is a plan view of a mount for artificial teeth embodying our invention, and showing an upper jaw set of teeth 55 mounted thereon;

Figure 2 is a similar view of the mount with the teeth and the diatoric teeth supports removed;

Figure 3 is a vertical longitudinal sectional view taken on the line 3—3 of Fig. 1, and 60

Figure 4 is a transverse sectional view taken on the line 4—4 of Fig. 2.

In the specific embodiment of the invention shown in the drawings, the numeral 1 designates a strip of cardboard, wood, fiber, 65 or other suitable substantially inflexible material, the said strip being preferably of a length sufficient to receive a set of artificial teeth arranged side by side as shown in Figure 4. Substantially centrally of the 70 length of the strip 1 is formed a depression or recess 2 of a width and length adapted to receive the supporting pins 3 of the six central teeth 4 of the set, the said depression or recess 2 being filled with wax or 75 other suitable penetrable and soft material 5. It will be understood that the teeth 4 are supported on the mounting by inserting the pins 3 into the wax 5, as shown in Figures 1 and 3.

80 The diatoric teeth 6 are mounted upon the strip or backing 1 at the respective ends of the depression or recess 2, the said diatorics being provided with transverse openings 7 through which passes a supporting 85 wire 8 having its ends inserted through openings 9 formed in the backing 1, the said ends of the wires 8 being twisted or otherwise detachably connected at 10 on the reverse side of the supporting strip 1. 90

95 It will thus be seen that all of the teeth of a set may be mounted upon the backing 1 in an attractive and firm manner with a minimum amount of wax. The backing 1 is also substantially rigid and inflexible and will not be affected by changes in temperature as is the usual wax mounting. The large or diatoric teeth are securely fastened upon the backing 1 by the wires 8 so that they cannot be easily knocked off or displaced, as is possible when the teeth are mounted in the wax. The diatorics are also arranged at opposite ends of the central teeth 4 so as to provide in effect buffers for these teeth to prevent the same from being accidentally displaced from the backing. Obviously the central teeth 4 can be removed from the backing by simply pulling the pins 3 out of the wax and replaced by pressing the pins into the wax, while the 100 105 110

diatorics can be easily removed by untwisting or disconnecting the ends of the wires 7 and pulling one end thereof from the corresponding opening 9, thereby allowing the 5 teeth to be slipped therefrom.

Having thus described the invention, what we claim is:

A mount for a set of artificial teeth including central or pin teeth and end or 10 "diatoric" teeth all in their natural relative positions, comprising an insert of penetrable material of sufficient area to support

said pin teeth, a backing of relatively impenetrable material having end portions adapted to underlie the end or "diatoric" 15 teeth, said backing supporting said insert between said end portions in such position that it will underlie the pin teeth, and means on both said end portions of the backing for securing the end or "diatoric" teeth to said 20 end portions.

FREDERICK MAEULEN.
GEORGE L. VAN ALLEN.
